SPACE CONDITION RESPONSIVE INSTRUMENT

Robert Eugene Emmons, Goshen, Ind., assignor to
Penn Controls, Inc., Wheaton, Ill., a corporation
of Delaware

Filed May 2, 1967, Ser. No. 6,924

Term of patent 14 years

(Cl. D52—7)

Fig. 2.

Fig. 1.

FIGURE 1 is a top and front perspective view of a space condition responsive instrument embodying my new design; and

FIGURE 2 is a bottom and front perspective view thereof.

The rear of the space condition responsive instrument is substantially flat in appearance, except for the top and bottom corner cutouts shown at the left rear of FIG. 1. Thereof.

The essential features of the design reside in the portions shown in solid outline.

I claim:

The ornamental design for a space condition responsive instrument, substantially as shown and described.
